UNITED STATES PATENT OFFICE.

HALBERT K. HITCHCOCK, OF PITTSBURGH, PENNSYLVANIA, ASSIGNOR TO PITTSBURGH PLATE GLASS COMPANY, A CORPORATION OF PENNSYLVANIA.

APPARATUS FOR HANDLING GLASS SHEETS.

Application filed June 9, 1926. Serial No. 114,643.

The invention relates to apparatus for handling and turning over glass plates. The apparatus is designed particularly for picking up glass plates from one car or carrier upon a track, lifting it vertically from the said car or carrier high enough to clear the workmen, then carrying it laterally above the workmen to a position above a second car or carrier on a second parallel track and depositing it on a second handling apparatus, that turns the glass plate over, lowers it, and deposits it onto the second car or carrier.

The invention has for its objects the provision of improved means for accomplishing the function as above set forth, but in particular, the novel means for turning over, lowering and depositing the glass plates onto the second carrier by the use of but one driving means. One embodiment of the invention is illustrated in the accompanying drawings, wherein:

Figure 1 is an end view of the apparatus in the direction of the arrows at the line I—I of Fig. 3. Fig. 2 is a plan view of the apparatus with some of the detail construction omitted so as to show the vacuum frames clearly. Fig. 3 is a section on the line III—III of Fig. 1, but shows the stripping frame raised in position ready to travel laterally over the workmen to the position over the second track. Fig. 4 is an enlarged side view of the sliding crosshead which controls the turning over. Fig. 5 is a plan view of the crosshead shown in Fig. 4. Fig. 6 is a section through the end of the turnover frame mounting on the line VI—VI of Fig. 7. And Fig. 7 is a section through the end of the turnover frame mounting on the line VII—VII of Fig. 6.

Referring to the drawings, 1 and 2 are a pair of parallel tracks upon each of which is mounted a series of cars or carriers 3, 4, such cars serving as a means for carrying the sheets of glass, secured to their tops, beneath a series of grinding and polishing machines as set forth in the Fox Patent No. 1,554,804. The track 2 is a return track upon which the cars carrying the glass, one side of which has been ground and polished, are returned to the starting end of the system, while track 1 extends beneath a second series of grinding and polishing machines. The apparatus

of the present application is designed to lift the sheets, having their upper sides ground and polished, vertically from the cars 4 to a position high enough to pass over the workmen's heads, then laterally to a position, over the car 3. The sheets are then deposited onto a second handling apparatus that turns the sheets over and lowers them to the table 3 where they are set in plaster of Paris in the usual manner.

Extending longitudinally of the tracks 5 is a crane runway consisting of the beams 5, 5 and upon this runway or track, is mounted a crane framework consisting of the longitudinal beams or girders 6, 6, and the transverse beams 7, 7, 7, 7, the framework being supported upon suitable wheels 8, 8. The wheels are connected by the transverse shafts 9, 9 and are driven by a suitable motor 10 through the compound gearing 11, 12, 13 and the gear 14 mounted on the left hand shaft 9 (Fig. 3).

At the right hand end of the crane is the vacuum lifting device 15 for lifting the sheets of glass from the return car 4 or for lifting new sheets from a table that is mounted over the cars 4. This table is not shown, but it is a stationary structure, under which the series of return cars 4 may pass. The sheets of glass as they are cut from the continuously formed ribbon can be packed on this table and as a new sheet is needed in the laying operation, the crane can pick it up, carry it over and lay it on one of the cars 3, as before described. The lifting device 15 is of the telescope design and the stationary cage 16 is supported by the beams 17, 17, and tied together by the horizontal beams 18, 18 (Figs. 2 and 3). It is carried on the transverse tracks 19, 19 mounted on top of the beams 7 by the wheels 20, 20, driven by a longitudinal shaft 21 by means of the motor 22, reducer 23, and spur gearing 24, 25, 26 and the gear 27 mounted on the shaft 21. A sliding cage 28, mounted inside of the cage 16 is supported by the cable 29, one end secured at 30 (Fig. 1) to the beam 17 and fed down over the sheave wheel 31, then up over the sheave wheel 32 and then down over the sheave wheel 33 carried in the yoke 34, which also carries the sheave wheel 31. The cable 29 is then fed up over a grooved drum 35, mounted on the shaft 36, and driven by the gear 37,

the pinion 38, the reducer 39 and the motor 40. The sliding cage 28 is supported from the yoke 34 by means of the pivot 41 connected to the bottom of such cage. The frame 15 is thus raised and lowered slowly by the cable 29. Mounted to the bottom of the sliding cage 28 by means of the brackets 42 is a multiple cup vacuum frame 43, comprised of a longitudinal beam 44 carried in the brackets 42. Bolted to the beam 44 are the vacuum cup brackets 45 at the end of which are bolted the vacuum cups 46. These cups are mounted loosely and are provided with a vertical movement, as shown at 65 (Fig. 7), in order to compensate for irregularities in the sheets to be handled. The vacuum is supplied by the vacuum pump 47 driven by the motor 48; and connected to the tank 49, to which the suction is applied. It is controlled from the operator's cage 50 by the valve 51, the control pipe 52 leading to the distributing pipes 53, which are connected to the vacuum cups 46, shown in Figs. 2 and 3. The vacuum lifting apparatus 15 is designed to travel laterally on the tracks 19 carried by the main crane beams 7, 7, so that it can run directly over the turnover frame 54 in order to deposit the sheet of glass thereon. The control mechanism of the lifting frame 15 is so arranged and timed that the frame must be raised vertically to a position high enough to clear the platform 55 before any lateral movement can be started. This provides against accidents that might occur from the frame 15 traveling laterally before it is up high enough to clear the platform 55.

Referring to Fig. 1, the vacuum turnover and laying apparatus is carried on the left hand side of the main crane, the center line 56 of the turnover frame 54 being in line with the center line of the tracks 1 and the table 3. The guide frame castings 61, 61 are bolted to the transverse beams 7, 7, 7, 7 and the platform structure by means of the hangers 57, 57, 57, 57. The longitudinal beams 58, 58, 58 form a means for supporting the turnover drive and the platform 55. The turnover and laying apparatus is composed of two vertical telescoping members, one at each end of the crane, composed of bearing castings or members 59, 59 mounted on the ends of the pipes 60, 60 that slide vertically in the castings 61, 61. The frame 54 is mounted in the bearing members 59, 59 and is rotated and lifted by the chains 75, 75 passing around the sprockets 74, 74 on the turnover shaft or pivot 62 (Figs. 6 and 7). This shaft is carried in the bearings 59 and carries the vacuum cup brackets 63, at each end of which are supported the vacuum cups 64. These cups are provided with a slight vertical movement shown at 65 to allow for slight variations in the sheets. The vac-

uum cups are connected from the vacuum pipe 66 (Fig. 7) by means of the branch pipes 67, the rubber hose members 68 and the pet cock connections 69, which enable the workmen to disengage any vacuum cup on the frame at any time to allow for broken sheets. The shaft 62 is hollow and the vacuum pipe 66 is carried into the center through the centering spider 71, thus reducing to a minimum the twisting on the 75 vacuum hose 72. Secured to the ends of the shaft 62 by means of the keys 73 are the sprockets 74, carried in the bearings 59 in such a way that the chains 75 can be fed down the left hand pipes 60 (Fig. 1) around 80 the sprockets 74, and back up through the right hand pipe 60 to the operating mechanism, mounted above.

Referring to Figs. 1, 4 and 5, the turnover and laying drive comprises the motor 85 76, the silent chain drive 77, the worm reducer 78, mounted on the stand 79. The horizontal shaft 80 carries two crank discs 81, 81, upon each of which is mounted a crank pin 82, to which is connected the rods' 90 83. Each of these rods is pivoted at 85 to a lever 84 pivoted at 86 to the platform 55 by the brackets 87. The upper end of each lever 84 is forked and carries a crosshead 88 (Figs. 4 and 5), to which it is secured 95 by the pivot 89. The pivots 89 also act as a means for attaching the clevises 90 to the levers 84. Attached to the end of each clevice 90, by means of an adjusting turnbuckle 91, is one end of the turnover 100 chain 75.

The crossheads 88 are hollow and provide guides for slidably holding the rods 93, which are provided at the left hand ends with shoulders or stops 94, to which 105 are connected the adjusting turnbuckles 95. Eye bolts 96 in the ends of the turnbuckles 95 provide the connections for the other end of the chains 75. The right hand ends of the rods 93 are attached at 97 to chains 110 98, carrying the counterweights 99 at their other ends. The levers 84 move back and forth in the direction of the arrows (Figs. 1 and 4) in performing the turnover and laying operation, and are actuated by the 115 rods 83 from the crank discs 81, 81.

Referring to Fig. 1, the turnover and laying frame 54 is in the laying position with the vacuum cups placing a sheet of glass 110 on the table 3. The vacuum frame 54 is held in a horizontal position or against rotation on the shaft 62 by means of the counterweights 99, the chains 98, which support such counterweight passing over the sheave pulleys 100 carried in the brackets 101 supported by the main crane beams 7. The counterweights pull the shoulders 94 on the rods 93 tight against the ends of the crossheads at 102 (Fig. 4). This causes the chains 75 to be pulled tight around the 130

sprockets 74, thus holding the frame in a horizontal position by the gravity action of the counterweights 99, 99. After the glass has been laid on the table 3, the motor 76 is started and the crank discs 81 rotate in the direction of the arrow, or to the right, thus pushing the rods 83 and the levers 84 to the right and causing the crossheads 88 to move to the right. Due to the gravity action of the counterweights 99, 99, the chains 75 move to the right over the sheave wheels 103, 104 carried on the top of the guide casting 61, thus lifting the frame 54 vertically and holding it in a horizontal position. After the levers 84 travel to the right a distance far enough to lift the frame 54 up, so as to clear the table 3, while turning over with a sheet of glass, the top of the bearing 59 come in contact with the bottom of the guide casting 61 (Fig. 1). This stops the vertical movement of the frame 54, but the levers 84 continue to move over to the right. This extra travel pulls the left hand side of the chain 75 through the clevice 90, thus moving the rod 93 and chain 98 to the left and raising the counterweight 99. This movement of the chain causes the frame 54 to rotate on the shaft 62 in the direction of the arrows, shown around the center y . After the lever 84 has traveled to its extreme right hand position, as shown (dotted) at 105 (Fig. 1), the frame 54 is in the dotted line position 106 with the vacuum cups turned up ready to receive another sheet of glass from the frame 15.

The vacuum lifting frame 15 now picks the glass up from the car 4, or from the storage table heretofore referred to, and raises it vertically to the dotted line position 109 (Fig. 1). It then carries it laterally over the platform 55 (which serves to protect the men working in the laying and turnover yard) to a position directly above the table 3 and above the dotted line position 106 of the inverted vacuum frame 54. The sheet of glass is released from the frame 15, allowing it to drop onto the frame 54, after which the vacuum is applied by means of the valve 107 and the pipe 108. The frame 15 then travels back to the dotted line position 109 ready to pick up another sheet of glass. Upon starting the motor 76, the lever 84 starts to move toward the left, thus releasing the tension on the clevice 90 and allowing the chain 98 and rod 93 to move to the right and rotate the frame 54 through 180 degrees to bring the glass down. After the rod 93 travels to the right a given distance while the crosshead 88 travels to the left, the shoulder 94 on the rod engages the end of the cross head at 102, thus stopping the rotation of the frame 54, the stop in conjunction with the counterweights 99, holding it in a horizontal position. The

lever 84 continues to move still further to the left, and this movement then lowers the whole frame 54 down over the table 33, after which the vacuum is released and the plate drops down onto the table covered with plaster of Paris for holding it firmly in position. The parts are proportioned and adjusted so that the crank discs 81, 81 travel over through an arc of 180 degrees and back during this operation.

The controls for manipulating the stripping, laying, and turnover crane and frame are carried in the cab 50 supported from the main crane beams 7, 7, 7, 7 and the guard platform 55, this cab being located on the guard platform and at the center of the crane so as to give the operator a good view of all the operations and adds to the efficiency of the apparatus. The apparatus has been described in the operation of shifting the glass sheets from the cars 4, inverting them and placing them upon the cars 3, but it will be obvious that this operation may be reversed, if desired, the sheets being lifted from the cars 3, inverted, and then placed upon the cars 4.

What I claim is:

1. In combination in apparatus for moving glass sheets to and from a surfacing table and inverting them, which consists of a vacuum frame mounted above the table for vertical movement toward and from the table and for movement around a horizontal axis to invert the frame, power means for moving the frame vertically, and automatic means operated by said power means for causing the vacuum frame to rotate about said axis to bring it to inverted position when the frame has moved upward a predetermined distance.

2. In combination in apparatus for moving glass sheets to and from a surfacing table and inverting them, which consists of a vacuum frame mounted above the table for vertical movement toward and from the table and for movement around a horizontal axis to invert the frame, power means for moving the frame vertically, and automatic means operated by said power means for causing the vacuum frame to rotate about said axis to bring it to inverted position when the frame has moved upward a predetermined distance, the said means being operative to turn the frame back to its first position when the frame is lowered.

3. In combination in apparatus for moving glass sheets to and from a surfacing table and inverting them, which consists of a vacuum frame mounted above the table for vertical movement toward and from the table and for movement around a horizontal axis to invert the frame, power means for moving the frame vertically, stop means for limiting the upward movement of the frame, and means actuated by the continued opera-

75

120

125

130

tion of the power means, after the upward movement of the frame is stopped, for causing it to rotate about said axis to bring it to inverted position.

5 4. In combination in apparatus for moving glass sheets to and from a surfacing table and inverting them, which consists of a vacuum frame mounted above the table for vertical movement toward and from the 10 table and for movement around a horizontal axis to invert the frame, power means for moving the frame vertically, stop means for limiting the upward movement of the frame, and means actuated by the continued operation 15 of the power means, after the upward movement of the frame is stopped, for causing it to rotate about said axis to bring it to inverted position, said means being operative on a further movement of the power 20 means, to turn the frame back to its first position of rotation preliminary to lowering it bodily to its starting position adjacent the table.

5. In combination in apparatus for moving glass sheets to and from a surfacing table and inverting them, which consists of a vacuum frame mounted above the table for vertical movement toward and from the table and for movement around a horizontal 30 axis to invert the frame, power means for moving the frame vertically, a wheel member carried by the frame for rotating it, a flexible supporting member looped around said wheel member with its two parts or 35 sides extending upwardly, means including a power device for moving both of said sides of said loop member upward together to lift the frame without rotating it, means for stopping the upward movement of the frame, and means whereby the continued 40 actuation of the flexible supporting member by the power means gives it a bodily longitudinal movement to rotate the wheel member and invert the frame.

45 6. In combination in apparatus for moving glass sheets to and from a surfacing table and inverting them, which consists of a vacuum frame mounted above the table for vertical movement toward and from the 50 table and for movement around a horizontal axis to invert the frame, power means for moving the frame vertically, a wheel member carried by the frame for rotating it, a flexible supporting member looped around

said wheel member, with its two parts or 55 sides extending upwardly, means for moving both sides of the loop member upward together, including a power device connected to one of said sides and a counterweight connected to the other side, means for stopping 60 the upward movement of the frame, and means whereby the continued actuation of said power means gives the flexible member a bodily movement in the direction of its length, thus lifting the counterweight and rotating said wheel member to invert said frame.

7. In combination in apparatus for moving glass sheets to and from a surfacing table and inverting them, which consists of a vacuum frame mounted above the table for vertical movement toward and from the table and for movement around a horizontal axis to invert the frame, power means for moving the frame vertically, a wheel member carried by the frame for rotating it, a flexible supporting member looped around 70 said wheel member with its two parts or sides extending upwardly, means for moving both sides of the loop member upward together, including a power device attached to one of said sides positively and to the other side with a lost motion connection, a counterweight also attached to said other side, means for stopping the upward movement of the frame, and means whereby the continued actuation of said power means gives the flexible member a bodily movement in the direction of its length, thus lifting the counterweight and rotating said wheel 75 member to invert said frame.

8. In combination in apparatus for moving glass sheets to and from a surfacing table and inverting them, which consists of a vacuum frame mounted above the table for vertical movement toward and from the table and for movement around a horizontal axis to invert the frame, and power means and connections arranged to move the frame 80 upwardly a predetermined distance without any movement of rotation and then upon a further forward movement of said power means to give the frame a movement of rotation about said axis to invert it.

In testimony whereof, I have hereunto 85 subscribed my name this 8th day of June, 1926.

HALBERT K. HITCHCOCK.
